UNITED STATES PATENT OFFICE.

HAROLD J. BELL, OF WOODBURY, NEW JERSEY, ASSIGNOR TO THE WELS-BACH INCANDESCENT GAS LIGHT COMPANY, OF NEW JERSEY.

INCANDESCENT GAS-LAMP.

SPECIFICATION forming part of Letters Patent No. 408,072, dated July 30, 1889.

Application filed March 21, 1888. Serial No. 267,986. (No model.)

To all whom it may concern:

Be it known that I, HAROLD J. BELL, a citizen of the United States, residing at Woodbury, in the county of Gloucester and State 5 of New Jersey, have invented new and useful Improvements in Incandescent Gas-Lamps, of which the following is a specification.

This invention relates to that class of incandescent gas-lamps in which an incandescent device—such as a mantle, hood, cap, or frame of refractory material—is suspended above the gas burner or burners.

The invention consists in the combination 15 of a group of gas-burners arranged in an annular series around a central burner, a series of incandescent mantles suspended above said gas-burners, one mantle being over each burner, and a globe or chimney surrounding 20 the entire group or cluster of burners and incandescent mantles, whereby an unbroken wall of light will be presented on every side from which the cluster is viewed.

The invention also consists in the construction 25 and combination of the parts of an incandescent gas-lamp, as will be hereinafter more fully set forth.

In the annexed drawings, illustrating the invention, Figure 1 is a top view of my im- 30 proved incandescent gas-lamp with burners and incandescent mantles grouped in a cluster. Fig. 2 is a sectional elevation of the same.

The numeral 1 indicates a portion of a gas-supply pipe. 2 is a coupling screwed on said 35 pipe; and 3 is a burner-base having a threaded neck 4, that is screwed into the upper end of the coupling. A number of radial gas-tubes 5 project horizontally from the upper part of the burner-base 3, and each of these radial 40 tubes is provided with an elbow-joint 6 at its outer end. In each elbow-joint 6 is supported a vertical burner-tube 7, and a central burner-tube 7^a is supported in the top of the burner-base.

45 Each burner-tube 7 and 7^a supports a burner 8, having a number of fine perforations or gas-exits 9 in its top, and each burner is surrounded by an air-tube 10, having lateral air-inlets 11, this air-tube in turn being sur- 50 rounded by a cup-shaped mantle-protector

12, having lateral air-inlets 13, through which a supply of air is admitted for both the interior and exterior surfaces of the mantle.

A separate mantle, hood, or frame 14 is suspended above and around each burner 55 from rings 15 on the upper ends of vertical rods 16, which are adjustably supported, by means of screws 17, in lugs or studs 18, projecting laterally from each burner or its surrounding air-tube. Between the coupling 2 and burner-base 3 is supported a gallery 19 for holding a globe or chimney 20, that surrounds the entire group or cluster of burners and incandescent mantles. It will be observed that this arrangement of a group of gas-burners 60 and incandescent devices within a single globe or chimney permits the use of a large mantle with each burner without involving any liability of contact between the mantles, and yet producing with a central burner and 65 mantle the appearance of a solid wall of light on all sides of the lamp.

Any number of burners can be placed around a central one at such intervals that the incandescent device suspended over the 70 central burner will be opposite to and cover all the spaces between the outer burners and their incandescent devices, so that when the lamp is lighted an unbroken line of light will be presented on all sides, thereby giving a 75 large and brilliant illumination.

When the lamp is placed where it can be reached by the hand, or it is for other reasons desired to have the gas-cock at the base of the lamp, the coupling 2 may be dispensed 80 with, the gallery being in such case secured between the base of the burner and the gas-cock by passing the nipple or threaded neck on the base of the burner down through a hole made for the purpose in the center of 85 the gallery, and running over the protruding nipple or threaded end of the burner the female end of the gas-cock.

In the drawings I have shown an incandescent gas-burner of the character described 90 and claimed in Letters Patent No. 390,056, granted to me September 25, 1888; but I would have it understood that I do not herein claim that or any other particular form of burner, my present invention being confined 95 to

to an incandescent gas-lamp comprising a cluster of gas-burners and suspended mantles surrounded by a single globe or chimney, the burners and incandescing mantles being 5 so arranged as to present an unbroken wall of light from every direction in which the lamp is viewed.

What I claim is—

An incandescent gas-lamp comprising a 10 cluster of gas-burners, one of which is central, while the others are grouped around it, a

number of incandescent mantles, each suspended separately above a single gas-burner, and a globe or chimney surrounding the entire cluster of burners and incandescent mantles, substantially as described. 15

In testimony whereof I affix my signature in presence of two witnesses.

HAROLD J. BELL.
